(57) **CLAIM**

The ornamental design for a retractable passenger seat, as shown and described.

DESCRIPTION

FIG. 1 is a perspective view of a retractable passenger seat, showing our new design.

FIG. 2 is a front elevation view of the retractable passenger seat of FIG. 1.

FIG. 3 is a rear elevation view of the retractable passenger seat of FIG. 1.

FIG. 4 is a right side elevation view of the retractable passenger seat of FIG. 1.

FIG. 5 is a left side elevation view of the retractable passenger seat of FIG. 1.

FIG. 6 is a top plan view of the retractable passenger seat of FIG. 1.

FIG. 7 is a bottom plan view of the retractable passenger seat of FIG. 1; and,

FIG. 8 is front perspective view of the retractable passenger seat of FIG. 1, showing other retractable passenger seats used with the retractable passenger seat of FIG. 1.

Portions or features of the retractable passenger seat not shown in the drawings form no part of the claimed design. The broken lines in the drawings form no part of the claimed design.

1 Claim, 8 Drawing Sheets
